US00D732730S

(12) **United States Design Patent**
Wang et al.

(10) **Patent No.:** US D732,730 S
(45) **Date of Patent:** ** Jun. 23, 2015

(54) **SPLICABLE LAMP PANEL**

(71) Applicant: **General Luminaire Co., Ltd.**, Taipei (TW)

(72) Inventors: **Yung-Hong Wang**, Taipei (TW); **Qin Zhou**, Shanghai (CN)

(73) Assignee: **General Luminaire Co., Ltd.**, Taipei (TW)

(**) Term: **14 Years**

(21) Appl. No.: **29/498,492**

(22) Filed: **Aug. 5, 2014**

(51) **LOC (10) Cl.** 26-99

(52) **U.S. Cl.**

USPC **D26/120**

(58) **Field of Classification Search**

USPC D26/9, 10, 12, 13, 15, 16, 24, 51, 61, D26/72, 76, 80, 81, 85, 86, 88, 90, 113, 118, D26/119, 120, 122, 128, 129, 138, 143, D26/144; D13/180; D10/93, 114

(57) **CLAIM**

The ornamental design for a spliceable lamp panel, as shown and described.

DESCRIPTION

FIG. 1 is a perspective view of a spliceable lamp panel showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

The broken lines shown in FIG. 8 illustrate portions of the spliceable lamp panel that form no part of the claimed design.

1 Claim, 6 Drawing Sheets
